UNITED STATES PATENT OFFICE.

OSCAR J. RANKIN, OF ST. LOUIS, MISSOURI.

TOOL.

Application filed July 30, 1923, Serial No. 654,657. Renewed June 1, 1925.

To all whom it may concern:

Be it known that I, OSCAR J. RANKIN, a citizen of the United States, residing at the city of St. Louis, in the State of Missouri, have invented certain new and useful Improvements in Tools, of which the following is a specification.

This invention relates to a tool by means of which it is possible to reach and conveniently operate valves and the like which are located in places not easily accessible. For example, it may be used to turn the drain-cocks of the radiator or gasoline supply of an automobile without compelling the operator to assume an awkward and uncomfortable position while doing so, as is necessary without the use of this tool.

Other objects and advantages will appear as the description proceeds.

In the accompanying drawings forming part of this specification, in which like numbers of reference denote like parts wherever they occur;

Figures 1 and 2 are a plan view and an elevation, respectively, of the complete tool;

Fig. 3 is a fragmentary perspective view showing the manner of applying the tool to the lever of a pet-cock; and

Fig. 4 depicts how the handle of the tool may be used to loosen an unusually tight filler-cap on a gasoline tank.

The tool proper consists of a cylindrical rod 1, preferably of steel or wrought iron, having its end portions 2 and 3 flattened to an oblong cross-section, the broad sides 4 and 5 of the respective end portions 2 and 3, for the sake of simplicity in its manufacture and for greater ease of manipulation, preferably lying in the same plane. The end portion 2 is bent back upon itself on its narrow sides 6 to form a loop 7, which serves as a convenient handle. The end portion 3 is bent on its narrow sides 8 to form an arm 9 perpendicular to the cylindrical part of the rod 1. The free end 10 of the arm 9 is then bent a half turn 11 on its broad side 5 to a U-shape form having a slot 12, the bend being on an axis parallel to rod 1.

In using the tool to operate the levers of pet-cocks or the like, which are located in places not easily accessible, as, for instance, the drain-cock 13 of a radiator 14, the arm 9 is placed in juxtaposition to the lever 15 of the pet-cock 13, with the lever 15 pro-

jecting into the slot 12 of the tool, so that the arm 9 and its free end 10 straddle the lever 15, as shown in Fig. 3. The lever 15 can then be turned by the operator's twisting the wrist of the hand with which he holds the tool, the rotary movement being transmitted through the rod 1 to the lever 15.

The tool handle 7 may be used to loosen an unusually tight filler-cap 16 on a gasoline line tank 17, as shown in Fig. 4, the handle 7 being inserted in the slot 18 of the filler-cap 16, and a turning movement imparted to the rod 1, in screwdriver fashion, the hand being applied to the arm 9.

The tool can also be used as a gage for indicating the amount of gasoline in a tank by inserting the handle 7 into the filler-opening of the tank and letting it touch the bottom of the tank, and then withdrawing the tool from the tank and noting the height to which it has been wetted by the gasoline, a series of marks 19 being inscribed on the sides of the tool to indicate the quantity of gasoline still remaining in the tank.

Having thus described this invention, I hereby reserve the benefit of all changes in form, arrangement, order, or use of parts, as it is evident that many minor changes may be made therein without departing from the spirit of this invention or the scope of the following claims.

I claim:

1. A tool of the character described comprising a rod having one of its ends flattened to rectangular form, the flattened portion being bent into a loop to form a handle, and having the other of its ends bent to form a perpendicular arm, the free end of said arm being bent a half turn about an axis parallel to the main portion of said rod, the flattening providing a slot with flat parallel sides.

2. A tool of the character described comprising a rod having end portions of oblong cross-section, and an intermediate cylindrical portion, one of the said end portions being bent into a loop to form a handle, and the other of said end portions being bent on its narrow sides to form an arm, the free end of said arm being bent on its wide sides to a U-shape.

In testimony whereof I hereunto affix my signature.

OSCAR J. RANKIN.
